AMPLIFIER SYSTEM

Benjamin F. Miessner, Short Hills, N. J., assignor,
by mesne assignments, to Radio Corporation of
America, New York, N. Y., a corporation of
Delaware

Application February 2, 1929, Serial No. 337,148

16 Claims. (Cl. 179—171)

The present invention relates to signal and like current amplifying systems, and particularly those employing thermionic amplifier devices. More particularly it relates to amplifier systems employing three electrode vacuum tube amplifiers energized from unsteady energizing sources capable of introducing disturbing effects, such as hum, in the translating devices usually associated with amplifier systems.

An object of the invention is to economize in the amount of filter material going to make up the filter system interposed between the source of unsteady energy and the electrodes of the tubes energized therefrom by not endeavoring to obtain a complete or very high order of suppression of the unsteady or ripple component of the energy, but relying instead upon controlling the effects of the ripple component of the current without disturbing the useful amplifying characteristics of the system. To this end I make use of special features for opposing the ripple component arising in one part of the system by the ripple component arising in another part of the system, and controlling the magnitude and phase of these opposing components.

In my copending application Serial No. 251,807 of February 4, 1928, now Patent 1,806,813 issued May 26, 1931, I show one form of hum neutralizing arrangement in an amplifying and reproducing system. The present invention is an improvement over said arrangement with features additional thereto, particularly in the matter of avoiding interference with amplification of signal currents.

The features of the present invention will be more fully understood by reference to the figures of the accompanying drawing in which like reference characters represent like parts so far as possible.

Fig. 1 is a diagrammatic showing of a single stage of three electrode vacuum tube amplification including the features of my invention.

Fig. 2 illustrates a modified form of my invention employed in a modified form of a stage of amplification.

Referring to Fig. 1 a three electrode vacuum tube VT has an input circuit including an input transformer T_1 and an output circuit including an output transformer T_2 . The tube and circuits may be, for example, the last stage of a multi-stage cascade connected amplifier. The electrodes of the tube are shown energized from an alternating current source through primary winding P of transformer T , such as a commercial 55 60-cycle lighting system. Secondary windings S_1 ,

S_2 and S_3 provide for heating the tube filament, the filament of a rectifier tube RT , and supplying current for rectification respectively, the rectified current being delivered to a filter system comprising filter condensers C_3 and C_4 and filter inductance L , the positive and negative terminals of the filter being as indicated. The negative terminal is shown grounded at G , as to a metallic support or housing for the organization of apparatus.

The positive terminal of the filter is connected to the plate electrode of the tube through primary of output transformer T_2 , and the negative terminal of the filter is connected to the filament by way of ground G , grounded resistor R_1 and 15 potentiometer K . Resistor R_1 is chosen of such value that the plate current flowing therethrough develops the desired amount of potential for negatively biasing the grid by way of the grounded connection of the grid circuit 20 through resistance R_2 .

I show a condenser C_1 connected between the filament and plate circuit of the tube, which condenser has sufficiently low impedance to the signal or other currents being amplified to bypass to a large degree these currents from the filter system and grid bias resistor R_1 . By so doing feed back effects between the output and input circuits of tube VT is to large degree eliminated, thus permitting the current amplification in the tube to be substantially normal. The by-passing of the signal current away from the filter system prevents developing signal voltages therein which could couple with other tubes or parts of a multi-stage system having other tubes supplied from the same filter, which coupling, because of the large amplification factor that may exist between removed stages of amplification, may cause serious undesired regenerative or degenerative effects. Furthermore, the removal of the resistor R_1 from the signal current path eliminates signal energy loss therein, leaving more signal energy available to the output device.

In my prior patent application referred to I showed a condenser connected in similar manner to condenser C_1 , but for the purpose of increasing the amount of ripple current from the filter flowing through bias producing resistor R_1 in order to control the rippling potential on the grid in a way to control hum elimination by grid neutralization. A condenser of suitable capacity for this purpose is not in general of sufficiently large capacity for audio frequency signal current bypassing, so that a by-pass condenser adequate in 55

the position of C_1 , and for its purpose in this application would permit too much ripple current to pass through bias resistor R_1 if this condenser were in the position referred to in my copending application, thus producing an excessive ripple voltage on the grid resulting in an undesirable degree of hum in the reproducer.

To permit of using an adequately large capacity condenser for signal current by-passing without producing excessive hum, I make a circuit connection between the plate and grid circuits including a condenser C_2 , and insert a resistance R_2 between the connection of this circuit to the grid circuit and the negative terminal of the source of supply or filter system, the connection to the negative terminal being indicated by way of grounded connections, but may be direct by wire connection. This connection permits of developing in resistance R_2 a ripple potential applied to the grid of phase opposed to the ripple potential applied to the grid from resistance R_1 , so that its excess potential may be neutralized. By choosing the values of condenser C_2 and resistance R_2 of proper amounts the ripple on the grid can be controlled in any desired way. It can be completely neutralized, or an excess of either phase can be left by over or under neutralizing. An excess may be desirable in many cases, as when it is desired to oppose hum currents arising in preceding stages of a multi-stage amplifier, or when it is desired to pass some residual hum current from the output of the tube to neutralize hum current in succeeding stages of amplification or in a sound reproducer as, for example, a so-called dynamic reproducer having its field energized by the filter current.

For complete neutralization condenser C_2 and resistance R_2 may have the same values as condenser C_1 and resistance R_1 respectively, though complete neutralization can be had when the values differ, but condenser C_2 must be large when resistance R_2 is small and vice versa. If condenser C_2 and resistance R_2 are made variable and adjusted not only can control be had over the amplitude but the phase as well, thus permitting generating in the circuits of tube VT a phased hum current opposed to a certain phase of hum current arising elsewhere.

Analyzing the system as connected and energized, there are at least three sources of the hum developed in the secondary of the transformer T_2 . First, the energization of the filament of the tube VT by alternating current causes a fluctuation in the plate current thereof through the electrical and temperature effects, independently of whether the grid and plate are energized with absolutely steady unidirectional current or whether the grid and plate are energized by means of the potentials developed by fluctuating current. Second, the grid, when energized by potentials developed by fluctuating current, causes a change in the impedance of the tube VT giving rise to hum in the secondary of the transformer T_2 . Third, the fluctuating current energization of the plate circuit causes introduction of hum into the secondary of the transformer T_2 .

The frequency of the hum developed by the filament, when energized by 60 cycle alternating current, is predominantly 120 cycles, as is well known.

The frequency of the hum developed by the other two sources is dependent upon the character of the rectifier tube RT. If of the half wave type the frequency is predominantly 60 cycle for

a 60 cycle source, and if RT is of the full wave type, as shown, the frequency is predominantly 120 cycle.

In my application above referred to I showed RT as a half wave rectifier and described in detail how the hum energy in the supply circuit could be fed back into the grid circuit to neutralize the hum produced by the fluctuating potential energization of the grid. 5

Thus in the present application the adjustments provided and described permit utilizing the hum arising in the plate circuit, i. e. the B hum, to neutralize the hum of the grid circuit, i. e. the C hum, and also the hum produced by the alternating current energization of the filament, i. e. 15 the A hum.

In the arrangement of Fig. 2 the details of the supply and filter system are omitted, the terminals of the filter being indicated by terminals B- and B+. In this figure I show what is termed 20 a condenser and choke coupling of the reproducer device LS to the output of the tube VT. The choke of this combination is the inductance L_1 and the condenser is the condenser C_1 in series with reproducer LS. In this case the signal currents are choked by L_1 direct to the filament by 25 way of condenser C_1 and reproducer LS, and thus avoid in large measure feed back effects. In the neutralizing ripple circuit I show a choke coil L_2 in addition to condenser C_2 to introduce an inductive effect to better permit of phasing to match 30 the inductive effect due to the inductive effects of the winding of the reproducer LS in series with condenser C_1 , and inductance L_1 .

Having thus described my invention, what I 35 claim is:

1. In a signal current amplifying system including an amplifier tube having grid-filament and plate-filament circuits, a source of uni-directional pulsating current, one terminal of which is 40 connected to the plate of said tube, and the other terminal of which is connected through a resistance to the filament of said tube, means within said plate-filament circuit for impressing excess pulsations from said source across said resistance, 45 connections between said grid-filament circuit and said resistance whereby the average potential of said grid is maintained at a known value relative to that of said filament, and means for impressing on said grid pulsations from said source of a phase 50 opposite to that of said excess pulsations.

2. In a signal current amplifying system including an amplifier tube having grid-filament and plate-filament circuits, a resistance, a source of uni-directional pulsating current, one terminal 55 of which is connected to the plate of said tube and the other terminal of which is connected through a portion of said resistance to the filament of said tube, said grid-filament circuit including said resistance, whereby the average potential of said 60 grid is maintained at a known value relative to that of said filament, means for impressing in predetermined degrees excess pulsations from said source across said portion of said resistance and means for impressing on said grid pulsations 65 from said source of a phase opposite to that of said excess pulsations.

3. In a signal current amplifying system including an amplifier tube having grid-filament and plate-filament circuits, a resistance, a source 70 of uni-directional pulsating current, one terminal of which is connected to the plate of said tube and the other terminal of which is connected through a portion of said resistance to the filament of said 75

5 tube, said grid-filament circuit including said resistance, whereby the average potential of said grid is maintained at a known value relative to that of said filament, means for impressing in 10 predetermined degrees excess pulsations from said source across said portion of said resistance and means for impressing on said grid pulsations from said source of a phase opposite to that of said excess pulsations, said means consisting of a variable condenser connected between said grid-filament circuit and a point within said plate-filament circuit between said source and said plate.

15 4. In a signal current amplifier system including an amplifier tube having grid-filament and plate-filament circuits, a source of uni-directional pulsating current, one terminal of which is connected to the plate of said tube, and the other terminal of which is connected through a resistance to the filament of said tube, a connection for impressing the potential developed in said resistance upon the grid of said tube, a signal current by-pass condenser shunting a portion of said plate-filament circuit whereby excess pulsations from said source are passed through said resistance, and means for impressing upon the grid of said tube pulsations from said source of phase opposed to said excess pulsations.

20 5. In a signal current amplifier system including a three-electrode vacuum tube having an input circuit and an output circuit including an inductive device, a source of uni-directional pulsating current, one terminal of which is connected to the plate of said tube through said inductive device and the other terminal of which is connected through a potential developing impedance to the filament of said tube, a connection for impressing the potential developed in said impedance upon the grid of said tube, a signal current by-pass condenser connected between said inductive device and said filament, whereby excess pulsations from said source pass through said impedance and means for impressing pulsations from said source upon the grid of said tube of phase opposed to said excess pulsations.

25 6. In a signal current amplifier system including a three-electrode vacuum tube having an input circuit and an output circuit including an inductive device, a source of uni-directional pulsating current, one terminal of which is connected to the plate of said tube through said inductive device and the other terminal of which is connected through a potential developing impedance to the filament of said tube, a connection for impressing the potential developed in said impedance upon the grid of said tube, a signal current by-pass condenser connected between said inductive device and said filament, whereby excess pulsations from said source pass through said impedance and means for impressing pulsations from said source upon the grid of said tube of phase opposed to said excess pulsations, said means including a variable condenser connected between said source-connected terminal of said inductive device and said grid filament circuit.

30 7. In a signal current amplifier system including a three-electrode vacuum tube having an input circuit and an output circuit including an inductive device, a source of uni-directional pulsating current, one terminal of which is connected to the plate of said tube through said inductive device and the other terminal of which is connected through a potential developing impedance to the filament of said tube, a connection for impressing the potential developed in said impedance upon the grid of said tube, a signal cur-

35 rent by-pass condenser connected between said inductive device and said filament, whereby excess pulsations from said source pass through said impedance and means for impressing pulsations from said source upon the grid of said tube of phase opposed to said excess pulsations, said means comprising a condenser and a second inductive device connected between said source-connected terminal of said first-mentioned inductive device and said grid-filament circuit of said tube.

40 8. In a signal current amplifier system including a three-electrode vacuum tube having an input circuit and an output circuit including an inductive device, a source of uni-directional pulsating current, one terminal of which is connected to the plate of said tube through said inductive device and the other terminal of which is connected through a potential developing impedance to the filament of said tube, a connection for impressing the potential developed in said impedance upon the grid of said tube, a signal current by-pass condenser connected between said inductive device and said filament, whereby excess pulsations from said source pass through said impedance and means for impressing pulsations from said source upon the grid of said tube of phase opposed to said excess pulsations, said means comprising a condenser and a second inductive device connected between said source-connected terminal of said first-mentioned inductive device and said grid-filament circuit of said tube, said inductive devices having substantially identical electrical characteristics whereby the fluctuation of space current in said tube is controlled.

45 9. In an amplifier system including an amplifying tube having grid-filament and plate-filament circuits and a source of power for said plate-filament circuit, the potential of which is irregular, the combination of a connection between one terminal of said source and the plate of said tube, said connection including a choke coil, a plurality of resistances connected between said grid and said filament, a connection between the other terminal of said source and a point between said resistances, an indicator and a capacity series connected between the plate terminal of said choke coil and said filament, and a capacity connection between the source terminal of said choke coil and the grid of said tube, whereby the fluctuation of the space current of said tube is controlled.

50 10. In an amplifier system including an amplifying tube having grid-filament and plate-filament circuits and a source of power for said plate-filament circuit, the potential of which is irregular, the combination of a connection between one terminal of said source and the plate of said tube, said connection including a choke coil, a plurality of resistances connected between said grid and said filament, a connection between the other terminal of said source and a point between said resistances, an inductive indicator and a capacity series connected between the plate terminal of said choke coil and said filament, and a capacity connection between the source terminal of said choke coil and the grid of said tube, said capacity connection including a phase modifying inductance whereby the fluctuation of the space current of said tube is controlled.

55 11. The method of energizing an amplifier system including an electron tube having A, B and C circuits, which consists in energizing the A circuit with alternating current, and energizing

- the B and C circuits with fluctuating unidirectional current and regulating the phase and amplitude of the fluctuating component of said fluctuating current applied to said B and C circuits 5 to neutralize the hum produced by the alternating current energization of the A circuit.
12. The method of energizing an amplifier system including an electron tube having A, B and C circuits, which consists in energizing the A circuit with alternating current, energizing the B and C circuits with fluctuating unidirectional current and regulating the phase and amplitude of the fluctuating component of said fluctuating current applied to said B and C circuits to neutralize the hum produced by the alternating current energization of the A circuit, and neutralizing the hum produced by the fluctuating current energization of the C circuit by excess pulsations from the B circuit.
13. In a signal current amplifying system including an amplifier tube having grid-cathode and anode-cathode circuits, a source of uni-directional pulsating current, one terminal of which is connected to the anode of said amplifier tube the other terminal of which is connected through a resistance to the cathode of said tube, said resistance being also included in the grid-cathode circuit of said tube, a path of low impedance to signals to be amplified connected between said anode and the cathode side of said resistance the impedance of said path being such that excess fluctuating components of said pulsating current from said source are fed therethrough and across the resistance whereby over-compensation for variations across the anode-cathode path of the tube due to the pulsating current from said source result, a capacity connected from the anode to the grid and a resistance connected from the grid side of said last-named capacity to the negative terminal of said source, for compensating the excess current fed by said path.
14. In a signal current amplifying system comprising an amplifier tube having grid-cathode and anode-cathode circuits, a source of uni-directional pulsating current and a resistance in series therewith forming part of said anode-cathode circuit, said resistance being also included in the grid-cathode circuit of said tube, whereby the average potential of said grid is maintained at a known value relative to that of the cathode, a path of low impedance to signals to be amplified comprising a capacity connected across said source and said resistance for forming a by-pass circuit for said signal currents around the source of pulsating current and said resistance whereby feedback effects between the output and input circuits of said tube are substantially eliminated, said path causing an excess flow of pulsating current through said resistance thereby producing an excessive ripple voltage on the grid and an undesirable degree of hum in the output circuit, and means comprising a capacity and a resistance forming a series circuit shunted across said source and a connection between a point common to said resistance and said capacity and the grid for producing compensating effects with respect to the excess current.
15. In a signal current amplifying system an amplifier tube having grid-cathode and anode-cathode circuits, a source of uni-directional fluctuating current and a resistance in series therewith forming part of the anode-cathode circuit, said resistance being also included in the grid-cathode circuit of the tube whereby the average potential of the grid-electrode with respect to the cathode is maintained at a known value, a path of low impedance to signal energy comprising a capacity connected between the anode and cathode of said tube for forming a by-pass circuit for the signal currents around the source of pulsating current and the resistance whereby feedback effects between the output and input circuits of said tube are substantially eliminated, the impedance of said path being inherently low for the fluctuating current components of energy from said source whereby excessive fluctuating components are by-passed through said capacity and across said resistance and impressed upon the grid-cathode circuit, an impedance element in the grid-cathode path and means for impressing across said impedance element a fluctuating current component of phase and magnitude to compensate for the effects of said excess fluctuating components.
16. In a signal current amplifying an amplifier tube having an anode, a cathode and a control electrode, a source of pulsating uni-directional current, a bias resistor, a connection external said tube between the anode and the cathode thereof including the source of uni-directional current and the bias resistor in series, an auxiliary resistor, a connection external the tube from the control electrode to the cathode thereof including the auxiliary resistor and the bias resistor in series, a connection between the anode and cathode electrodes of said tube including a capacity having low impedance to signal currents to by-pass the signal currents from said source and the bias resistor, said capacity and said bias resistor forming a shunt circuit across said source of uni-directional current whereby alternating current components from said source are by-passed through said bias resistor, a capacity shunted from said anode to the grid side of said auxiliary resistor, said second capacity and auxiliary resistor also forming a circuit shunted across the source of uni-directional current whereby hum frequencies are also by-passed through the auxiliary resistor, and means for adjusting said capacities and resistors with respect to each other so that the effect of the hum frequencies impressed across one of the resistors is substantially compensated by the hum frequencies impressed across the other resistor.

BENJAMIN F. MIESSNER.
